UNITED STATES PATENT OFFICE.

JOHN O. NEIKIRK, OF LOMBARD, ILLINOIS, ASSIGNOR TO WINE RAILWAY APPLIANCE CO., OF TOLEDO, OHIO, A CORPORATION.

RAILWAY-DOOR LATCH.

Application filed April 4, 1923. Serial No. 629,794.

This invention relates to improvements in railway door latches, and has for its object the production of a latch suitable for use in latching and locking doors of cars which are 5 arranged to be opened so as to unload the car through the bottom or the sides of the car.

Of the accompanying drawings Fig. 1 is a fragmental elevation of the lower portion of a gondola car with latches applied thereto 10 which embody the features of my invention; Fig. 2 is an enlarged elevation of one of the latches; Fig. 3 is a sectional view along the line 3—3 of Fig. 1; Fig. 4 is a sectional view along the line 4—4 of Fig. 2; Fig. 5 is a sectional view along the line 5—5 of Fig. 2; and Fig. 6 is a reduced elevation of one of the latches when partly closed.

In this instance, as a preferred form of the application of my invention, I have shown a 20 latch applied to a dump car 10 for the purpose of holding closed the door 11. The door is hinged to the car by means of hinges 12 fixed to one of the center sills of the car in any suitable manner. Beams 14 extend 25 across the bottom of the door, and the latches 15 are suitably fixed to the side of the car for the purpose of holding the beams 14, and hence the door, in place when the door is closed. The latch and locking means 30 comprise a hook 16 pivoted to the side of the car at the point 17, and a lock 18 pivoted at the point 19 and adapted to be turned downwardly to hold the hook in place under the flange of the beam 14 when the door is 35 locked.

In a general way the latch and locking means are similar to such means now in use, but my invention consists in the specific arrangement and shape of the various parts 40 used; and it is to be understood that the latch may be used with doors in the bottom of gondola or hopper cars or other similar cars, or for dump trucks, without any particular reference to just where the door is located.

I have found that in the operation of latches for this purpose it is frequently difficult to entirely close the door even when the car is empty, and particularly when a 45 portion only of the material has been dumped, and to assist in this and at the same time to hold the door firmly closed and to avoid any undue wear or tendency to break the latch, I provide a latch so shaped and suspended that it may be used to force the 50 door closed and so that it will also firmly and

suitably support the beam 14 when the door is closed. By the use of the beam 14 a large flat surface 21 is provided and a corresponding surface 22 becomes the supporting and wearing surface of the hook. When the hook is in the closed position, as indicated, these two surfaces being entirely in contact there is much less wearing of the parts than is the case when smaller surfaces are in contact. At the same time it is desirable to have the hook so formed and suspended that the toe 23 will pass under the edge 24 of the flange, as indicated in Fig. 6, before the door is entirely closed so that by forcing the hook 60 towards the locking position the door will be forced thereby to the closed position, the surface 22 acting as a cam on the flange surface 21. To accomplish this I suspend the hook by the pivot 17 so that a perpendicular 65 25 therefrom to the extension of the surface 22 will strike the extension, as indicated, outside of the surface. That is the hook is suspended at a point to one side of a perpendicular to its bearing surface. As a consequence 70 of this arrangement all points of the surface 22 will pass away from the surface 21 as soon as the latch is moved from its closed position, but the outer points will pass away more rapidly, and all points will come firmly 75 in contact with the surface when the hook is 80 in its closed position. Hence, in closing the door the edge 24 of the surface 21 will bear on the cam surface 22 so as to gradually take the stress off from the toe 23 of the hook as 85 the pressure on the hook increases, and when 90 the door is substantially closed the downward force is on the inner portion of the hook instead of on the toe 23.

However, I do not wish to confine myself 95 to surfaces 21 and 22 which are exactly parallel with the edge of the door, as substantially the same result could be arrived at if the surface were inclined somewhat one way or the other.

Inasmuch, as the hook 16 must support a 100 very considerable weight, I have so provided the supporting means as to amply support the hook and also to prevent binding thereof, and to allow convenient assembling of the device. For this purpose I provide 105 bosses or trunnions 26 projecting from and integral with the hook 16, the inner boss being supported in the wood 27 and on the side beam 28 of the car, and the outer boss passing into an opening 29 in the bracket 20. 110

I thus provide means whereby the hook is amply supported and eliminate the tendency of dirt or other materials to lodge in the device and work into the bearings of the support so as to prevent relative rotation of the parts; and in case it is desired to replace any member of the device the hook and bracket may be very easily separated or assembled. This arrangement also materially increases the strength of the supporting portion of the hook as no pivot opening is required. Also the beam 28 may be narrower as the trunnion rests on the beam while a rivet support would need to pass through the beam.

The bracket 20 may be supported at the side of the car in any suitable manner such as by means of an offset flange 30 having a rivet 31 connecting it to the side of the car. At the same time a rivet 32 is provided for the support of the bracket and for the pivot of the locking means 18. This rivet 32 is adapted to pass through the hub 33 of the bracket, the hub 34 of the locking means and the beam 28 fixed to the side of the car.

The lock 18 in a very general way is similar to locks now in use. It is formed so as to force the hook in place as the lock is forced into the locking position. But, as such locks are ordinarily formed, there is a tendency for the lock to gradually work out of place owing to the pressure of the latch on the cam surface 36 of the lock. To prevent this tendency I form the cam surface 36 so that its centers of curvature lie somewhat below the center of the rivet or pivot 32. As a consequence the upper portions of the cam surface are closer to the pivot than the lower portions and the tendency of the pressure of the latch 16 on the surface 36 is to force the lock downwardly instead of upwardly. Thus the lock forces the hook into the latching position whether the lock is forced upwardly or downwardly from a certain position. I then provide a stop to prevent the lock from moving downwardly too far. Any suitable stopping means may be provided. I prefer for the purpose a boss 37 fixed to the lock 18 and so positioned as to come in contact with the bracket at the point 38 when the lock is in the desired position. Inasmuch as the pressure of the latch on the surface 36 tends to force the lock downwardly the danger of the door becoming unlocked is eliminated; and a counterweight 50 on the lock also tends to prevent its becoming unlocked.

In order to hold the lock 18 in its open position I provide on the lock a stop 39 which comes in contact with the shoulder 40 on the bracket when the lock is turned backwardly to release the latch. In order to strengthen the device and provide free space for the lock so as to prevent any tendency of the lock 18 to bind on its pivot, I provide a boss 41 integral with the hub 33 of the

bracket, and this boss forms the pivot for the hub 34 of the lock, and the inner end 42 of the boss resting against the beam 28 prevents binding of the lock when the rivet 32 is riveted in position.

I also provide suitable means to assist in latching and unlatching the door. I prefer for this purpose a stud 45 fixed to and projecting outwardly from the lower portion of the hook. This stud may be used as a handle for forcing the hook when latching or unlatching the door, or it may be used as a fulcrum of a lever for the same purpose. If a bar 46 is placed in the position shown in Fig. 6, by pressing downwardly on the outer end of the bar, not only will the door be forced upwardly into its closed position, but also the hook will be forced into its latching position. In a somewhat similar manner the bar and stud 45 may be used for forcing the hook out and unlatching the door. This is illustrated in Fig. 1. By resting the bar 46 against the end of the beam 14 as a fulcrum the latch may be forced open by means of the stud 45. It is to be understood however that other ways of using the stud and other means than the stud may be provided.

In some cases, particularly where one latch only is used on a door, there is sometimes a tendency for the door with the beam 14 to be forced away from the latch and thus to allow the door to open. To prevent this I provide a finger or stop 48 which is fixed to or integral with the bracket 20. When the door is closed the end of the beam 14 is prevented by this stop from moving away from the hook, and the slanting surface 49 guides the beam to the proper position as the door is being closed.

I claim as my invention:

1. In a railway car a hook for holding a door in its closed position, a cam for locking said hook in its holding position, and stops fixed to said cam for limiting the movement of said cam in its locking and its unlocking movement.

2. In a railway car a hook for holding a door in its closed position, a cam for locking said hook in its holding position, said cam having stops for limiting its movement in its locking and its unlocking position, and a weight fixed to said cam for holding it in its locked position.

3. In a railway car a door latch comprising a bracket, means integral with said bracket for holding the door against lateral movement, and a hook pivotally supported by said bracket for holding the door closed.

4. In a railway car a door, forming a portion of the bottom of the car, a door latch comprising a bracket, a hook pivotally supported by said car for holding said door closed, and a stop fixed to said bracket to prevent horizontal movement of said door,

5. A door latch for railway cars comprising a door latch bracket, a latch mounted therein, and a door stop mounted on said bracket in a predetermined fixed relation to said bracket.

6. A door latch for railway cars comprising a door latch bracket, a latch mounted therein, and a door stop cast integral with said bracket in a predetermined fixed relation to said latch.

7. In a railway car, a door and a door latch, said latch comprising a bracket, a hook supported by said bracket and a cam for locking said hook, and co-acting stop members for limiting the travel of the lock in its locking and unlocking movement, said members being fixed respectively to said bracket and to said lock.

8. A door latch comprising a bracket adapted to be fixed to a door frame, door holding means movably fixed to said bracket and adapted to pass under a portion of a door associated with said frame, a stop fixed to said bracket for preventing movement of said door portion away from said means, and other means for forcing said holding means towards said stop; whereby said door may be held closed and prevented from moving away from said holding means.

9. A door latch comprising a bracket, a door stop fixed to said bracket, a second stop movably mounted on said bracket; door holding means movably mounted on said bracket between said stops, said three elements being substantially in the same plane, and said second stop when in one position being materially nearer said door stop than when in another position, and means for

preventing movement of said second stop, when in its nearer position, away from said door stop.

10. In a railway car, a hook for holding a door closed, and a cam for locking said hook in its holding position, said cam being arranged to force said hook toward its holding position when said cam is being moved to its unlocked position.

11. In a railway car a pivotally supported latch for holding the door closed, a cam coacting with said latch to lock it in its closed position, said cam being formed to move said latch toward the holding position when the cam is rotated to lock or unlock said latch.

12. The combination of a door, a frame surrounding said door, a movable latch for holding the door closed, and a cam co-acting with said latch to lock it in its closed position, said cam being arranged to move the said latch towards its holding position when the said cam is operated to unlock said latch.

13. A door latch comprising a bracket adapted to be fixed to a door frame, door holding means movably associated with said bracket and adapted to engage a portion of a door associated with said frame, a stop fixed to said bracket for preventing movement of said door portion away from said means, and other means for forcing said holding means towards said stop, whereby said door may be held closed and prevented from moving away from said holding means.

In testimony whereof, I hereunto set my hand.

JOHN O. NEIKIRK.
